UNITED STATES PATENT OFFICE.

ELMER GRANT STILL, OF LIVERMORE, CALIFORNIA.

AVIATION DEVICE.

Application filed March 8, 1924. Serial No. 697,953.

My invention relates to improvements in aviation devices in which rotating radial vanes are used for the purpose of creating a partial vacuum on a surface by virtue of 5 centrifugal force, and the objects of my invention are: to provide a simple, efficient and comparatively small and light-weight device for lifting and propelling aircraft; to attain bird efficiency in flight (it having 10 been found by experiment that many birds lift at the rate of between 100 and 200 pounds per horse-power used, while airplanes lift only about 20 and helicopters about 40 pounds per horse-power); to produce a "still flyer," or device that will stand 15 still while flying, or hover in the air, and arise and alight perpendicularly; to provide a propelling and lifting device that (contrariwise to the screw propeller) will 20 be more efficient at high than at low speeds of revolution and will have as much lifting power per horse-power when hovering as when moving forward (relative to the air); to provide an efficient propelling and lifting 25 device having no regularly working parts to wear out and get out of order; to make aircraft practically self-balancing, to reduce the dangers of flying to a minimum, and other objects hereinafter mentioned.

I attain these objects by the mechanism 30 illustrated in the accompanying drawings, in which—

Fig. 1 is a view, in central vertical section, of one form of the device; Fig. 2, a 35 plan view of the top of the principal revolving part of the device on the line 2—2 and minus the hollow frustum; Fig. 3, a cross section of the lower half of the principal revolving parts of the device on a level 40 with the upper circular rims *i* (the line 3—3); Fig. 4, a view, in central vertical section, of another form of the device.

Similar letters refer to similar parts 45 throughout the several views.

In the preferred form of the device, the improvement over previous aviation devices attempting to use this principle of centrifugal force to create a partial vacuum on a surface by means of rotating radial vanes, 50 consists in the downwardly-rushing air being prevented from striking tops of vanes in entering the spaces between the vanes at the top, which would thus produce considerable downward pressure; also, in means

(a central cylinder or equivalent obstruction) being provided to prevent the air in entering the body of the device or spaces between the vanes from entering closely around the central axis, where the centrifugal force is very small comparatively; also, 55 in means being provided for regulating the degree of the lift-giving or thrust-giving partial vacuum during the operation of the device without changing the speed of revolution; also, in the centripetal back-flow of 60 air toward the partial vacuum being prevented, several such means being provided, thus conserving and increasing the partial vacuum; also, in means being provided for regulating during the operation of the device the size of the openings through which the air enters the device at or near its top; also, in its being made possible to regulate 65 the distance between the top and the bottom of the principal revolving parts of the device; also, in the device being more strongly 70 built and braced by reason of its structural arrangement, and other improvements hereinafter explained. However, not all these 75 improvements (even only a few of them) 80 designed for the preferred form of the device need necessarily be embodied in the device, which would then simply be not quite so efficient.

In order to accomplish the objects of my 85 invention, I make use of centrifugal force, by means of thin radial vanes *a*, preferably (though not necessarily) taller than wide, which (in the preferred form of the device and when used for lifting instead of forward 90 propulsion) are mounted vertically on a horizontal disc *b*, the union being air-tight and these vanes extending from the periphery of the disc to about half-way to its center, where they are attached air-tightly 95 to a vertical cylinder *c*, mounted centrally and air-tightly on said disc, and these vanes sloping off (in an angle or curve) at their tops, the slope being downward and away 100 from center, and the tops of these vanes being covered entirely or partly with a sloping roof, or hollow frustum *a'*, preferably attached to the tops of these vanes *a*.

The rapid revolution of the disc *b*, with its 105 mountings, on its central vertical axis *d* (to which it is attached) by the engine *e*, causes the air to enter the openings at and near the top of the vanes *a* and be thrown

out radially by centrifugal force; the air being thus thrown out radially the distance of the width of the vanes (say, one foot) before it, or much of it, can find its way 5 downward for the distance of, say, four feet, representing the height of the vertical vanes.

The result is the production of a partial 10 vacuum just above the top side of the horizontal disc *b* (excepting, of course, the part covered by the central cylinder *c*); and if one-twentieth of a complete vacuum were thus produced there, the resulting lifting 15 force would be 1/20 of 14.7 pounds (the air pressure per square inch at sea level) times 144 (the number of square inches in a square foot) times 9.4248 (the number of square feet in a 4-foot disc minus $\frac{1}{4}$ for the area of the bottom of the 2-foot central cylinder *c*), which gives 997.52 pounds lift.

In the preferred forms of the device, as 20 shown in Figs. 1 and 4, (and when the device is arranged vertically, i. e., for lifting), there is no head resistance (or downward pressure) at the top of the vertical vanes 25 resulting from the air rushing rapidly downward there and striking these tops during the rapid revolution of the device, owing to the fact that the air enters the spaces between the vanes entirely from toward center (horizontally or approximately so) and thus strikes the inner vertical or nearly vertical edges of the vanes *a* or *a'* near their tops, instead of entering at the horizontal open 30 tops of the vanes (vertically, or axially), as in previous devices of this kind.

Furthermore, the air, upon entering horizontally or somewhat downwardly from toward center would quickly be thrown by 40 centrifugal force against the under side of the hollow frustum, or roof, *a'*, thus maintaining an air pressure there at least equal to, if not greater than, the atmospheric pressure on the upper side of this roof, and in the latter case producing additional lift by 45 reason of the pressure being greater on the under side.

It is by reason of the vanes extending 50 higher than the cylinder and sloping at their tops and being preferably covered partly or entirely with the sloping roof, in conjunction with said central cylinder, that the air is caused to enter the device proper centrifugally (from toward center) instead of axially (vertically) and yet is prevented 55 from entering closely around center.

As the centrifugal force imparted to the 60 entering air tends to throw it out at right angles to the central axis, while the suction (or, rather, downward atmospheric force) toward the partial vacuum tends to throw the air axially downward, the result of the operation of these two forces is that the air is thrown downward and outward at an angle of about 45 degrees, or practically parallel 65 with the slope of the tops of the vanes.

Hence the addition of the sloping roof is not entirely necessary, except perhaps where the air first enters, at the topmost part of the vanes. The slope of the roof should, of course, be at least steep enough to maintain 70 the prevailing atmospheric pressure on the under side.

Another advantage of this sloping roof is that it does away with the friction of the 75 sloping top edges of the vanes with the outside air during the rapid revolution of the device, along all that portion that the roof covers.

A cylinder *a*² (Figs. 1 and 2) fits within the upper part of the central cylinder *c* and 80 has a framework *w*¹ attached to it and extending downward and fitting around the central shaft *d* as a sleeve, and a lever *a*³, pivoted at *a*⁴, is connected with said framework by means of the double rods *h*¹ and 85 their attached collar *h*², for operating said cylinder *a*² up and down as desired during the operation of the device and thus regulating (in conjunction with the roof *a'*) the size of the openings through which the air 90 rushes in near the top of the device and hence making it possible to regulate the amount of air coming into the device during its operation, as found best for different elevations, barometric pressures, speeds of 95 revolution and other varying conditions of operation, and in order to admit sufficient air at all times to maintain at least atmospheric pressure on the under side of the roof *a'* equal to that on the top side. 100

These vertical vanes would be made numerous enough to give the air between them sufficient rotary and centrifugal motion and to add sufficient strength and rigidity to the device, in conjunction with the roof *a'*. 105

It is a well-known fact that experiments made by M. Eiffel have proven that fully two-thirds of the lift of an airplane is due to the air-rarefaction, or negative air-pressure, or partial vacuum, formed on the upper side of the planes; and this invention (as used for lifting) aims to devote the engine power to producing such a lift-giving partial vacuum by means of a small, strong, lightweight device instead of using a large, fragile, heavy airplane or helicopter for the purpose. 110

Experiments have also shown that when thin surfaces, rather closely spaced, are moved very rapidly across the path of a very 120 rapid air current (the latter parallel with these surfaces), the head resistance of their edges is considerable; and in fact when the space between the surfaces is reduced still more—even though each space is many times as great as the thickness of the surfaces—the head resistance encountered by the edges is nearly equal to that of a solid surface of the same area as that traversed 125 by the surface edges; this being evidently 130

due to the fact that practically every particle of the rapidly-flowing air is struck by the edges of the rapidly-moving surfaces.

By the mathematical rule for calculating centrifugal force, it is found that this force increases directly in proportion to the increase in the weight of the whirling body or particles and also increases directly in proportion to the increase in the distance from center (radius). Hence at 10 inches from center the centrifugal force is 10 times as great as at one inch from center. And it is also found by this rule that centrifugal force increases with the square of the speed of revolution when the other two variable factors (weight and radius) remain the same. Hence at 1000 revolutions per minute the centrifugal force is 100 times as great as at 10 revolutions per second, instead of being only 10 times as great; and therefore a centrifugal flyer should be much more efficient at high than at low speeds of revolution, the power required increasing only directly with the increase in the speed of revolution; practically. Use is thus made of the principle that makes whirling winds, such as the tornado, so powerful, or efficient. This rule for calculating centrifugal force is as follows: Multiply the weight of the revolving body by the square of the velocity in feet per second (the velocity being found by multiplying the radius in feet by 2 and by 3.1416 and by the number of revolutions per second), and divide this product by the product found by multiplying the radius by 32.16 (gravity acceleration in feet per second).

If, instead of inserting the central cylinder *c*, the vanes were extended to the central shaft, their movement close to center would be so slow (comparatively) that very little centrifugal force would be given to the air there to carry it outward, and hence considerable air would easily find its way quickly downward along the central axis and tend to destroy the partial vacuum at the top side of the horizontal disc *b*; while the extra air thus received into the device would have to be thrown out from around the axis indirectly by centrifugal suction, instead of directly by centrifugal force, and hence be thrown out less efficiently and less completely.

I am aware that a device has been patented (U. S. Patent No. 1,090,322, issued March 17, 1914) having several sets of vertical radiating vanes, curving over at their tops and revolving at different speeds around the central axis, and having a convex (hemispherical) closure below covering only the central part of the space between these radiating vanes, besides having the whole central part of the device open to the air rushing downward toward the partial vacuum. In contrast to these features, my device is a

further improvement over such devices in that it needs only one set of revolving vanes, thus obviating much complicated mechanism and consequent waste of power, and preferably these vanes are flat or at least practically straight axially, so as to cause no downward pressure as the air rushes downwardly through the device, and likewise not even one set of revolving vanes need have their top edges exposed to such downward pressure; and it has means completely and airtightly closing the openings between the vanes at the bottom for a considerable distance from center, said closing means being, preferably, a flat disc or a disc with upturned edges (saucer-shaped, or concave, instead of convex), besides other means for preventing the centripetal back-flow of air toward the partial vacuum.

When used on aircraft for the purpose of forward propulsion, this device would, of course, have a horizontal position, instead of being in a vertical position as shown in the drawings.

To aid in maintaining the partial vacuum referred to, baffle plates *f f* are attached airtightly to the outer edges of the lower half (approximately) of each vertical vane or else between the edges of the vanes, these baffle plates extending vertically, preferably from an extension *q* of the disc *b*, and at a considerable angle to said vanes *a* and being preferably strengthened by circular rims, such as *i i*. These baffle plates beat back the air which tends to rush inwardly (centripetally) there to fill the partial vacuum forming just above the top side of the disc *b*.

Another means provided to aid in keeping the air from thus rushing inwardly consists of vertical strips *a⁵* and *a⁶* placed between the outer edges of the vanes *a* in a position at about right angles to these vanes and so as to close part of the space between the edges of these vanes at their lower part. The strips *a⁵* are attached airtightly to the edges of the vanes, extending from these edges at about right angles in the direction opposite to the direction of revolution of the device; while the strips *a⁶* have openings at each edge between them and the edges of the vanes. Each kind of these strips may be provided with baffle plates *f* at their edges. In the drawing, Fig. 3, the strips *a⁵* and *a⁶* are shown placed alternately around the periphery of the vanes *a*. These vertical strips *a⁵* and *a⁶* would preferably be positioned so as to be somewhat further from the center of the shaft *d* at the edge opposite to the direction in which the device revolves than at the other edge of the strip, so as to make it easier for the air to escape outwardly by centrifugal force.

Another set of baffle plates *g g* attached to two other circular bracing rims *i i* and

also to the rim of another horizontal disc or circular frame *j*, located under the main disc *b*. This second disc *j* is attached to a hollow driving shaft *k*, surrounding the main driving shaft *d*. A cog wheel *n*, on a shaft *o*, runs between an external gear *m* (attached to the main driving shaft *d*) and an internal gear *p* (attached to the hollow driving shaft *k*), meshing with both of these other gears, so that each of the two shafts, with its disc, set of baffle plates, etc., attached to it, is thus driven in the opposite direction from the other. This second set of baffle plates *g* is thus a further aid in beating back the air at the lower half of the periphery, or it may be used without the first set being installed, and it may be driven in the same direction as the disc *b*, only driven more rapidly, by so arranging the driving gears.

By eliminating the internal gear wheel *p*, this second set of baffle plates *g* may be made stationary, instead of revolving, acting then simply to beat back the air which tends to circle around the device in the direction of its revolution and enter the lower part of the device.

The engine *e* would preferably be a steam engine, so that engine failure would be practically impossible; and, owing to the greater lift per horse-power secured and the lighter weight of the device, it would be feasible to use heavier (and therefore stronger and more reliable) engines than those now used in aviation.

A hollow frustum of a cone *l*, having an angle of about 45 degrees, is arranged around the upper part of the revolving device, preferably with vertical sides *r* below it, so as to throw the air currents downward as they strike it after being thrown outward by centrifugal force. This frustum would thus aid in securing further lift—or, in the case of a device of this kind arranged horizontally, securing more thrust, or push—and, together with the vertical walls *r*, would also prevent outside air currents (relative to the device) from interfering with the equilibrium of the device.

The outer part of the disc *b* may be provided with a circular, vertical strip *t*, or with a circular strip *u* sloping outward and upward (preferably at a steep angle), mounted air-tightly on said disc, or with both such strips combined into one as shown, or with several of them spaced a distance apart. These would be a still further aid in maintaining the partial vacuum while the device is in action, by keeping the air from coming in at the bottom edge (centripetally) and by the sloping part *u* tending to throw upward and outward what little air does find its way to the bottom of the vanes.

Small holes *v* (Figs. 1 and 4), preferably vertical slots uniform for each vaned com-

partment, may be provided, preferably extending through the walls of the central cylinder *c* near the bottom thereof, together with a smaller cylinder *w* fitting tightly (air-tightly) inside of the larger cylinder *c*, 70 so that, by moving said inner cylinder upward, downward or around, the said slots will be partly or wholly uncovered, permitting outside air to rush into said compartments near the bottom during the operation 75 of the device and thus doing away with the partial vacuum there to a greater or less extent, as desired, without decreasing the speed of revolution; the hollow cylinders *c* and *w* each being at least partly open at top or bottom or both. A framework *x* (Figs. 1, 2 and 3) extends upward from said inner cylinder *w* and around the driving shaft *d* as a sleeve sliding on it, and a lever *y*, pivoted at *z*, is connected with said framework by means of the double rod *h* (which becomes a single rod just above the central axis *d*) and its attached collar *h*³, for operating said inner cylinder *w* up and down and thus varying the lifting force of the device 90 as desired. This would be useful in enabling the device to rest on the ground with the engine running at full power, also to suddenly rise or drop in the air, to be suddenly checked in its downward movement, as in 95 landing, and to land as gently as desired, all without changing the engine throttle.

The hollow frustum, or roof, *a*¹, may be attached to short radiating vanes *a*⁷ and to a framework *a*⁸ slidably mounted on the 100 shaft *d* near its top, with these short vanes *a*⁷ overlapping the vanes *a*, all as shown in Fig. 4, so that by sliding this framework and attached parts up and down on the shaft the distance between the roof *a*¹ and the disc *b* 105 may be varied during the revolution of the device and hence the amount of air intake varied accordingly (as well as by the cylinder *a*²). This would be especially useful for experimental purposes, in order to determine 110 the most efficient relative dimensions for the device.

This whole aviation device would preferably be built strongly of metal, such as welded sheet steel or duralumin or aluminum. It is shown mounted on a float *s*. By reason of the weight being mostly below the plane of lift, as shown, and outside air currents being prevented by the surrounding wall from interfering with the equilibrium 115 of the device, as above explained, the device would be practically self-balancing, although means for lateral and longitudinal balancing could easily be added if desired. Preferably, small reversible-bladed propellers 120 would be used for balancing and also for steering. Then, with a reliable steam engine, as above mentioned, it would make flying 125 quite safe.

This device could be attached, as a part, 130

to an airplane, dirigible, helicopter or other aircraft, either for lifting or for propelling; or it could be used alone, like a captive balloon; or similar or other means for forward 70
propulsion could be added to it; and several of these devices, revolving preferably in opposite directions or in balanced relation (whether side by side or one above another), could be used on the same aircraft.

10 I do not restrict my invention to the precise form or relative dimensions herein given, for it is plain that variations (such as having the vanes not exactly perpendicular to the disc, or the vanes being somewhat 75
15 curved or not being exactly radial but at an angle thereto) could be made from the specification herein given without departing from the principle of the invention.

Including such modifications and equivalents, I therefore claim:

1. In an aviation device, a disc; practically radial vanes mounted on said disc and extending from near the periphery of said disc part of the way to the center of said 80
25 disc; a large-diameter cylinder mounted centrally on said disc and to which said vanes are attached, and means for revolving said disc with its mountings, so that the incoming air will be thrown outward by centrifugal 85
30 force, thus creating a partial vacuum close to said disc on its vane-carrying side.

2. In an aviation device, an axis; a disc mounted centrally on said axis; a cylinder mounted centrally on said disc and axis; 90
35 vanes radiating from said cylinder; a covering at the ends of said vanes opposite to said disc; said covering sloping outwardly from its inner edge toward said disc; there being openings to admit air between said 95
40 inner edge and the end of said cylinder opposite to said disc (said cylinder extending only part of the way from said disc to said inner edge), and means for revolving the device on said axis, all substantially as 100
45 described.

3. In an aviation device, an axis; a disc mounted centrally on said axis; a cylinder mounted centrally on said disc and axis; vanes radiating from said cylinder; baffle 105
50 plates at the periphery of said disc and vanes, said baffle plates being positioned at an angle to said vanes, and means for revolving the device on said axis, all substantially as described.

55 4. In an aviation device, an axis; a disc mounted centrally on said axis; a cylinder mounted centrally on said disc and axis; vanes radiating from said cylinder; baffle plates at the periphery of said disc and 110
60 vanes, said baffle plates being positioned at an angle to said vanes; means for revolving the device on said axis; a second circular set of baffle plates, but positioned at an opposite angle and arranged to revolve in the 115
65 opposite direction from said first set, and

means for revolving this second set of baffle plates closely around the periphery of the first set and for the same purpose, but in the opposite direction, all substantially as 70
described.

5. In an aviation device, an axis; a disc mounted centrally on said axis; a cylinder mounted centrally on said disc and axis; vanes radiating from said cylinder; means for revolving the device on its axis; a circular set of baffle plates positioned at an angle to said vanes and the said set arranged to revolve closely around the periphery of 75
80 said vanes, and means for revolving said set of baffle plates, so as to aid in throwing the air out centrifugally.

6. In an aviation device, an axis; a disc mounted centrally on said axis; a cylinder mounted centrally on said disc and axis; vanes radiating from said cylinder; a narrow circular strip mounted on the outer part of said disc and being practically parallel with said axis, and means for revolving the device on said axis.

7. In an aviation device, an axis; a disc mounted centrally on said axis; a cylinder mounted centrally on said disc and axis; vanes radiating from said cylinder; a narrow circular strip mounted on the outer part of said disc, said strip sloping outward from 90
95 center at a considerable angle to said disc, and means for revolving the device on said axis.

8. In an aviation device, an axis; a disc mounted centrally on said axis; a cylinder mounted centrally on said disc and axis; vanes radiating from said cylinder; means for revolving the device on said axis; there being small holes through the bounding walls of the compartments formed by said 100
105 cylinder and vanes and disc, and means for opening and closing said holes partly or wholly as desired during the operation of the device, so as to admit outside air into said compartments and close said holes airtightly, 110
115 as desired.

9. In an aviation device, an axis; a disc mounted centrally on said axis; a cylinder mounted centrally on said disc and axis; vanes radiating from said cylinder and extending longitudinally of said axis; a sloping covering at the ends of the vanes opposite to said disc, said covering sloping outwardly from its inner edge toward said disc; there being openings to admit air between 120
125 said inner edge and the end of said cylinder opposite to said disc (said cylinder extending only part of the way from said disc to said inner edge); a second cylinder mounted telescopically with said first-mentioned cylinder at the end of the latter opposite to said disc; means for moving said second cylinder back and forth, during the operation of the device, so as to project more or less beyond the end of said first-mentioned cylinder.

der, thus varying the distance between the end of said second cylinder and said inner edge and thus regulating the amount of air admitted through said openings, and means for revolving the device on its axis.

10. In an aviation device, an axis; a disc mounted centrally on said axis; a cylinder mounted centrally on said disc and axis; vanes radiating from said cylinder and extending longitudinally of said axis; a sloping covering having radiating vanes attached to it on its side toward said disc and so placed that its vanes overlap the said first-mentioned vanes at the ends of the latter opposite to said disc, said covering sloping outwardly from its inner edge toward said disc; there being openings to admit air between the inner edge of said sloping covering and the end of said cylinder opposite to said disc (said cylinder extending only part of the way from said disc to said inner edge); means for moving said sloping covering back and forth in the directions of said axis during the operation of the device, so as to vary the distance between said inner edge and the end of said cylinder opposite to said disc, and means for revolving the device on its axis.

11. In an aviation device, an axis; a disc mounted centrally on said axis; a cylinder mounted centrally on said disc and axis; vanes radiating from said cylinder and extending longitudinally of said axis; a sloping covering having radiating vanes attached to it on its side toward said disc and so placed that its vanes overlap the said first-mentioned vanes at the ends of the latter opposite to said disc, said covering sloping outwardly from its inner edge toward said disc; there being openings to admit air between the inner edge of said sloping covering and the end of said cylinder opposite to said disc (said cylinder extending only part of the way from said disc to said inner edge); means for moving said sloping covering back and forth in the directions of said axis during the operation of the device, so as to vary the distance between said inner edge and the end of said cylinder opposite to said disc; a second cylinder mounted telescopically with said first-mentioned cylinder at the end of the latter opposite to said disc; means for moving said second cylinder back and forth, during the operation of the device, so as to project more or less beyond said end of said first-mentioned cylinder, thus varying the distance between the end of said second cylinder opposite to said disc and said inner edge, and means for revolving the device on its axis.

12. In an aviation device, an axis; a disc mounted centrally on said axis; a cylinder mounted centrally on said disc and axis; vanes radiating from said cylinder and extending longitudinally of said axis; strips

between the outer edges of said vanes, said strips being practically parallel with said axis and said strips closing part of the space between the edges of said vanes, and means for revolving the device on said axis, all substantially as described.

13. In an aviation device, a disc; a plurality of vanes rotatably disposed on one side of said disc, and means for creating a useful, thrust-giving partial vacuum on that side of said disc through the centrifugal action of said vanes while rotating.

14. In an aviation device, a disc; a central axis; a plurality of radially disposed rotatable vanes; a cover attached to said vanes for directing the air to enter the spaces between the vanes centrifugally instead of axially, the rotating vanes creating a partial vacuum on their side of said disc, and means for regulating the degree of the partial vacuum on said disc during the operation of the device otherwise than by regulating the speed of rotation of said vanes.

15. In an aviation device, a disc; a revolving cylinder centered thereon; a plurality of radially disposed vanes secured to said cylinder; means for directing the air to enter the spaces between the vanes centrifugally instead of axially; means for varying the speed of revolution, and means separate from the last-named means for regulating the degree of the partial vacuum on the vanes side of said disc during the operation of the device; said partial vacuum being created by the centrifugal force imparted to the entering air by the rotating vanes.

16. In an aviation device, a disc; a revolving cylinder centered thereon; a plurality of radially disposed vanes secured to said cylinder and disc; means for directing the air to enter the spaces between the vanes centrifugally instead of axially, a partial vacuum being created on the vane-carrying side of said disc by the centrifugal force imparted to the entering air by the rotating vanes, and means for preventing the back flow of air toward said side of said disc.

17. In an aviation device, a disc; a central axis; a plurality of radially disposed rotatable vanes, the rotating vanes creating a partial vacuum on their side of said disc, and means for regulating the degree of the partial vacuum on said disc during the operation of the device otherwise than by varying the speed of rotation of said vanes.

18. In an aviation device, a disc, a central axis, a plurality of radially disposed rotatable vanes, the rotating vanes creating a partial vacuum on their side of said disc by centrifugal action, and means for preventing the air from entering the device proper (that is, the spaces between the vanes) closely around said central axis during the operation of the device.

19. In an aviation device, a disc, a central axis, a plurality of radially disposed rotatable vanes, the rotating vanes creating a partial vacuum on their side of said disc by centrifugal action, and means for directing the air to enter the spaces between the vanes centrifugally instead of axially during the operation of the device. 40
20. In an aviation device, a disc, a central axis, a plurality of radially disposed rotatable vanes, the rotating vanes creating a partial vacuum on their side of said disc by centrifugal action, and means for regulating, during the operation of the device, the size of the openings through which the air enters the device at its end opposite to said disc. 45
21. In an aviation device, a disc, a central axis, a plurality of radially disposed rotatable vanes, the rotating vanes creating a partial vacuum on their side of said disc by centrifugal action, and means for regulating, during the operation of the device, the amount of air flowing into the device near its end opposite to said disc otherwise than by varying the speed of rotation of said vanes. 50
22. In an aviation device, a disc, a central axis, a plurality of radially disposed rotatable vanes, the rotating vanes creating a partial vacuum on their side of said disc by centrifugal action, and means for preventing the back flow of air toward the partial vacuum during the operation of the device. 55
23. In an aviation device, a disc, a central axis, a plurality of radially disposed rotatable vanes, the rotating vanes creating a partial vacuum on their side of said disc by centrifugal action, and means tending to prevent the air from entering said partial vacuum centripetally during the operation of the device. 60
24. In an aviation device, a disc, a central axis, a cylinder mounted centrally on said disc and axis, a plurality of radially disposed vanes secured to said cylinder and disc and extending further from said disc axially than does said cylinder, and means for revolving the device on said axis, thus creating a partial vacuum on the vane-carrying side of said disc. 65
25. In an aviation device, a disc, a central axis, a large-diameter cylinder mounted centrally on said disc and axis, a plurality of radially disposed vanes secured to said cylinder and disc, and means for revolving the device on its axis, thus creating a partial vacuum on the vane-carrying side of said disc. 70
26. In an aviation device, a disc, a central axis, a cylinder mounted centrally on said disc and axis, a plurality of radially disposed vanes secured to said cylinder and disc extending further from said disc axially than does said cylinder and sloping at their ends opposite to said disc, and means for revolving the device on its axis, thus creating a partial vacuum on the vane-carrying side of said disc. 75

ELMER GRANT STILL.
